UNITED STATES PATENT OFFICE.

LOUIS C. BISHOP, OF EAST NEW YORK, N. Y.

DESIGN FOR A TRAIL-PIECE FOR TOY CANNON.

SPECIFICATION forming part of Design No. 16,856, dated August 17, 1886

Application filed July 17, 1886. Serial No. 208,330. Term of patent 7 years.

To all whom it may concern:

Be it known that I, Louis C. Bishop, a citizen of the United States, residing at East New York, in the county of Kings and State of New York, have invented and produced a new Design for a Trail-Piece for Toy Cannon, of which the following is a specification, reference being had to the accompanying drawings.

My invention consists in a new and original design for a toy field-piece, the distinguishing feature of said design being a peculiarly-outlined trail-piece.

The design is fully illustrated in the accompanying drawings, in which Figure 1 represents a side elevation of the field-piece. Fig. 2 is a plan or top view of the same.

Similar letters indicate corresponding parts.

In the drawings, the letter A designates a field-piece, in which a represents a cannon, and b a carriage, both of which may embody any suitable design. The trail-piece C, as shown in Fig. 1, has its upper outline or face curving concavely downward at d from a horizontal portion, c. Then said outline curves downward convexly at e, and then gradually slopes concavely at a portion, f, and finally terminates in an upwardly curving or rolling portion, g. The lower outline or face consists

of a horizontal portion, c', a concave portion, c', a downwardly-sloping portion, f', and an upwardly-rolling portion, g'. The portions f and f' and g and g' of the outlines converge to form a nearly-pointed tail, g g'.

In Fig. 2, which illustrates a plan view of the field-piece, the trail-piece is shown to be 35 designed with a bifurcated portion, h, having on each of its ends longitudinal depressions i or other ornamentations. The sides j j of the trail-piece converge toward the tail g g'.

What I claim as new, and desire to secure 40 by Letters Patent, is—

The hereinbefore-described design for a toy field-piece, which consists in the trail-piece thereof having a horizontal portion and a downwardly curved or sloping portion which 45 terminates in an upwardly curved or rolled tail, the upper and lower faces of said trail-piece converging toward the tail, substantially as shown and described.

In testimony whereof I have hereunto set 50 my hand and seal in the presence of two subscribing witnesses.

LOUIS C. BISHOP. [L. S.]
